UNITED STATES PATENT OFFICE.

KENNETH L. CURTIS, OF NEW YORK, N. Y.

PROCESS OF REFRIGERATING.

Application filed February 28, 1922. Serial No. 539,881.

To all whom it may concern:

Be it known that I, KENNETH L. CURTIS, a citizen of the United States, and resident of New York city, in the county of New York and State of New York, have invented certain new and useful Improvements in Processes of Refrigerating, of which the following is a specification.

The invention relates to an improved process of refrigerating. The object of the invention is the provision of an improved and simplified process for refrigerating. The invention is particularly useful for maintaining a refrigerator intended for containing foods, etc., at a suitable temperature, the operation being one in which a suitable liquid refrigerant, water being preferred, is evaporated from a closed chamber within the space to be refrigerated, in such a manner as to constantly maintain the desired low temperature in the refrigerator. According to the preferred manner of practicing my process, I automatically maintain a static body of water or other suitable liquid refrigerant in a closed refrigerant chamber, and preferably by means of a continuously running constant speed pump, I maintain a partial vacuum over the surface of the water or other refrigerant to produce rapid evaporation so as to cause refrigeration within the refrigerating chamber, but the rate of evaporation is such, under conditions such as obtain in practical use of the device, as not to freeze the water or other refrigerating liquid which constitutes the refrigerant, the evaporation being conducted in such manner and at such rate as to maintain the temperature of the refrigerant somewhat above its freezing point, and according to the preferred manner of practicing the invention the air in the refrigerator is allowed to circulate by rising and traversing the refrigerant chamber, as by passing through openings therein where the heat is abstracted, the air thereafter again descending.

While this is the preferred manner of practicing the invention, it is to be understood that the invention is not to be limited to all of these features.

The invention consists in the novel features of the process hereinafter described according to the preferred manner of practicing the same, and in connection with the preferred apparatus for carrying out the

same, and the invention will be more particularly pointed out in the appended claims.

Other objects and advantages of the invention will more fully appear from the following description taken in connection with the accompanying drawings illustrating said preferred form of apparatus for carrying out the process.

In order that the invention may be more clearly understood attention is hereby directed to the accompanying drawings forming part of this application and illustrating one form of apparatus by which the process may be carried out. In the drawings Fig. 1 ⁷⁰ represents a somewhat diagrammatic view, partly in side elevation and partly in section, of the entire apparatus;

Fig. 2 is an enlarged section taken on lines 2—2 of Fig. 1, illustrating the vacuum pumping apparatus at one point in its operation;

Fig. 3 is a sectional view similar to that shown in Fig. 2 illustrating the vacuum pumping apparatus at another point in its operation;

Fig. 4 is a section taken on line 4—4 of Fig. 3;

Fig. 5 is a partial enlarged sectional view corresponding to the upper part of Fig. 2, ⁸⁵ and

Fig. 6 is a partial enlarged sectional view corresponding to the upper part of Fig. 3.

In accordance with the invention a liquid refrigerating medium, preferably water, is fed into a chamber which is located in a space to be cooled. I have illustrated a closed chamber, or container, 1, located within a refrigerator 2 adapted for containing food, etc., as in the usual domestic ice box, or refrigerator. The container 1 is preferably located within the refrigerator near the upper portion of the interior thereof, and may be supported by suitable supports 3, 3, which are preferably spaced inwardly somewhat from the outer walls of the refrigerator. The liquid refrigerating medium, preferably water, as stated, is fed into chamber 1 by a pipe 4. Means must be provided for maintaining the supply of liquid to chamber 1 to compensate for vapors which are withdrawn therefrom during the refrigerating process. Preferably the water or liquid level is maintained at a constant desired level, as illustrated for

example at 5, by means of a float valve, the valve 6 being illustrated as pivoted to the wall of container 1 and having an arm 7 carrying a float 8 secured thereto, the valve 6 closing when the liquid reaches the desired level and opening when the level falls, in the well known manner.

A suction pump is connected by pipe 9 to the interior of container 1. A partial vacuum is formed in chamber 1 by the operation of this pump which causes the refrigerating medium to evaporate and thus to give up heat, the amount of heat removed being practically proportional to the amount 15 of vapor removed from chamber 1. When water is used as the refrigerating medium, as is preferred, no provision need be made for condensing and using the same again. It also may be noted that the thermostat 20 and pressure control devices which are essential to the successful operation of various automatic refrigerating apparatus now in use, are not needed.

The chamber 1 is preferably provided with 25 a plurality of pipes 10 extending therethrough and opening at both ends into the space to be refrigerated. The members 3 which serve as supports for chamber 1 also preferably serve as partitions extending 30 from side to side of the refrigerator with openings 11 at the bottom thereof, so that when the device is in operation the warmer air will pass upwardly through the space between partitions 3 and the outer walls, 35 pass downwardly through the pipes or passages 10 where the heat is abstracted, and through the holes in shelves 12 and openings 11, the air then again passing up along the outside passages. The refrigerator may 40 be provided with perforated shelves 12 in the usual manner.

The vacuum pumping apparatus is shown as contained within the cylinder 13 and the crank case 14. The vacuum producing or suction apparatus is of improved 45 and novel design, constituting one of the features of the invention, and is particularly well adapted to produce an exceedingly low vacuum in chamber 1, which is necessary for or highly desirable in the operation 50 of the system.

The vacuum pump which is preferably used combines a zero-clearance outlet valve and a mechanically operated inlet valve. 55 The zero-clearance is obtained by making the outlet valve extend over the full diameter of the cylinder so that the piston may move to the extreme end of the cylinder or even overtravel without doing any damage. 60 The inlet valve preferably takes the form of a sleeve which seals the inlet opening by seating at its end in the manner of a poppet valve and not by sliding over a port to entirely cover or uncover the same, as is 65 customary with sleeve valves. By the use

of a mechanically operated inlet valve and an outlet valve of the character referred to I am able to obtain great efficiency and may produce an exceedingly low vacuum. By a mechanically operated inlet valve I mean 70 one which operates by mechanical means, independently of any difference of pressure on the opposite sides of the same, so that operation of the same will be certain even when operating under conditions of such 75 extreme vacuum, that there would not be enough pressure on either side of a valve to open the same at any time.

In the preferred form of the apparatus, as illustrated, the vacuum pump apparatus 80 comprises a pair of cylinders 13 and 15 which are secured to an air tight crank case 14, the cylinder 13 being shown as mounted on the upper end of the crank case, with its lower end opening into the same, while 85 the cylinder 15 is mounted within the lower portion of the crank case. The pistons of the two cylinders are connected to operate in unison, the piston 16 of the upper cylinder serving to draw water vapor, or generally speaking, the vapor of the liquid refrigerant, from chamber 1 in the refrigerator and to discharge the contents of the crank case through pipe connection 18 into a suitable receptacle 19. The two cylinders 95 are preferably the same in their construction, except that the lower is much smaller than the upper one.

The exhaust valves 20 and 21 of the cylinders 13 and 15 are preferably both of the 100 full diameters of the cylinders and may be considered as movable cylinder heads. They are held in place by springs, 22, in the case of the upper cylinder and 23 in the case of the lower cylinder, and are opened, 105 at the end of each outward piston stroke, by the pressure of the exhaust gases or vapor, or condensed liquid in the case of the lower cylinder, during the regular operation of the 110 chamber.

The inlet valves both preferably take the 115 form of sleeves as shown, the sleeve valve of the upper cylinder 13 being indicated at 24 and the sleeve valve of the lower cylinder being shown at 25. These sleeves surround the pistons and form in effect the cylinder walls. The upper sleeve 24 is preferably provided with an inclined surface 26 at its upper end which is adapted to seat against a correspondingly shaped surface 27 on the 120 valve seat 28, while the lower sleeve 25 is provided with a similarly shaped lower end surface 29 which seats against a similar seating surface on the seat 30. The sleeves are preferably moved in one direction by a 125 cam or similar mechanical device and in the other direction by spring action.

In the preferred form of the device, as 130 illustrated, the two cylinders 13 and 15 are diametrically opposed to each other and the

two pistons are operated in unison from the same wrist pin. As illustrated the two pistons may be connected together by a rod 31 in axial alignment with both of the same, a 5 connecting rod 32 being pivotally connected at its upper end to a pin 33 on piston rod 31 while the lower end of the connecting rod is pivotally connected to the pin 34 on a disc 35 secured to the shaft 36 which is constantly 10 rotated from a suitable motor or power device.

The two sleeves 24 and 25 are connected together, as by clamping members 37 and 38 secured respectively to the lower end of 15 the upper sleeve and the upper end of the lower sleeve, these clamps being secured together by rods 39 extending between the same (see Fig. 4). Disc 35 is preferably formed as a cam or eccentric, a roller 40 20 resting against the outer surface thereof. Preferably roller 40 is carried by an arm 41 having downwardly extending portion 44 above the cam disc 35, arm 41 being pivotally secured at its outer end, at 42 to the crank 25 case. The cam disc and roller 40 are utilized for moving the sleeve valves in one direction, while springs are used for moving the sleeves in the other direction, suitable springs being indicated at 43 secured at their 30 opposite ends to the clamping member 38 and the cylinder 15.

A push rod 45 for actuating the sleeve valves rests on or is secured to the upper portion of arm 41. Preferably push rod 45 35 is formed as a tube; for a purpose to be explained hereafter, this tube extending through a suitable opening in the clamping member 37, through an aligned opening in the top member 46 of the crank case and 40 into an aligned bore or passage 47 formed in cylinder 13, in which it is guided.

Preferably push rod 45 operates the sleeve valves through a spring 48 (see Figs. 2 and 3) which must be sufficiently stiff to move 45 the sleeves against the pull of springs 43 and yet be capable of being compressed by a slight overtravel of push rod 45 itself, so as to prevent possible damage of the parts in case the push rod tends to overtravel 50 slightly for any reason. Spring 48 may surround the rod or tubular member 45 between 55 a cup or abutment 49 secured to the rod, at one end, and a cup 50 at the other end which bears against the clamping member 37. Accordingly both sleeves will be moved upwardly by cam 35 and will be moved downwardly by springs 43 as soon as such movement is permitted by cam 35 during each operation of the pistons.

In the operation of the device as so far described, the pipe connection 9 which leads 60 to the evaporating chamber 1 in the refrigerator, is connected through the opening 51 in the upper head of cylinder 13 with a 65 passage 52 which leads into the interior of

cylinder 13, above piston 16, when sleeve 24 is away from its seat 27, as shown in Fig. 6.

In the regular operation of the system, air and water vapor, or other gases, will be sucked into the space above piston 16 on the 70 descending stroke of the latter, as shown in Figs. 3 and 6, inlet valve 24 then being opened and outlet valve 20 closed. Valve 24 will be moved upwardly against its seat about the time that piston 16 starts on its 75 return or upward movement so that outlet valve 20 will be moved from its seat against the pressure of springs 22 and the contents of the cylinder above the piston will be forced into passage 47 previously referred 80 to. The gases pass from passage 47 into the tubular member 45 which extends into the lower end of the same and pass out through an opening 53 in member 45 into the interior of the air tight crank case. 85

Piston 17 of the lower cylinder will be rising on its intake stroke as the upper piston is moving upwardly on its expelling stroke. Condensed water, or air and gases in the crank case, and surplus oil will pass through an opening 54 which extends through cylinder 15 of the lower pump member into an annular space 55 formed in the cylinder 15 surrounding sleeve 25. The sleeve being raised from its seat, as shown in Fig. 2, this material will be drawn into the interior of the cylinder, and when sleeve valve 25 closes and piston 17 descends, the outlet valve 21 will open and this material will be forced out through 100 pipe 18 into the container 19 shown in Fig. 1.

It will be noted that the outlet valves 20 and 21 of the two cylinders extend across the entire diameter of the cylinders and constitute what may be termed zero-clearance outlet valves, since the pistons may travel on their exhaust strokes to the full end of the cylinders, or may even over travel. Valves 20 and 21 may be considered as movable cylinder heads. 105

The pump pistons are designed to operate at high speed in the system described, and considerable power would be required if the upper piston had to operate at this 115 speed to withdraw air from chamber 1 at the beginning of the operation, when the entire system is filled with air at atmospheric pressure. Also the air thus drawn from the evaporating chamber 1 by the large upper cylinder and discharged into the crank case would be more than the small lower cylinder could remove in time to prevent the building up of a high pressure in the crank case, which would further increase the power required. Accordingly in the preferred form of the invention the lower cylinder alone is utilized at the beginning of the operation, the lower cylinder then withdrawing air from the in- 120 125 130

terior of the crank case and through connection 47 and a bypass connection 56 from the container 1. Pump cylinder 15 is considerably smaller in diameter than the upper pump cylinder and very little power is required to operate the same even with the entire apparatus full of air. Automatic means are provided, in the preferred form of invention to become effective, when a sufficient vacuum has been established in the system, to cut in the upper cylinder so that from this time on the larger capacity upper cylinder will be effective for maintaining vacuum and evaporating the water gases from chamber 1, the lower chamber serving from this time on merely to remove the air or gas, oil and condensed liquid from the crank case.

In the form of construction described bypass 56 extends from the inlet opening 51 through a valve opening 56¹, 57, into the space 58 at the upper end of the cylinder in which the outlet valve 20 is seated, this space 58 opening into the passage 47 which leads to the crank case. A valve 59 is positioned to seal the opening 56¹ extending from the horizontal portion of bypass 56 into the recess 57, when a sufficient vacuum has been established in the system, so as to shut off the bypass.

This valve 59 rests on a pile of air tight containers 60 (Figs. 5 and 6) which rest on a support 61 which extends across the construction within space 58. Containers 60 are thin hollow members, of what may be termed pill box construction, preferably formed of very thin metal. They are filled with air at atmospheric pressure, and will lie flat on each other on support 61 when the pressure surrounding them in space 58 and bypass 56 is atmospheric, in which case an opening will be provided over and around the containers, as is shown in Fig. 5. When this condition exists the lower pump cylinder will draw directly through passage 47 and bypass 56, from chamber 1, and the upper pump cylinder will be inoperative. After the lower pump has operated sufficiently to reduce the pressure in the crank case, containers 60 will expand because of the unbalanced pressure of the air confined inside the same, and valve 59 will be lifted and held against its seat at the top of space 57, as is shown in Fig. 6, whereby the bypass 56 will be closed and the upper pump cylinder rendered effective.

In the preferred construction of apparatus the wrist pin 33 is preferably mounted between ball bearings 62 and the crank pin 60 is similarly provided with ball bearings (not shown). The crank shaft 36 is preferably provided with a step bearing 63 to take the thrust caused by the vacuum in the crank case, the step bearing forming a seal 65 and preventing air from leaking into the

crank case at this point. Oil may be supplied to the face of this step bearing through pipe 64, the oil being slowly sucked into the crank case along the surface of the crank shaft 36 and thereby lubricating the crank shaft.

The remaining parts of the pumping apparatus are preferably lubricated by a single oil supply pipe 65, indicated in Figs. 1 and 4, which supplies oil to an annular recess 66 located between the upper cylinder sleeve 24 and the cylinder casing 13. This oil is sucked upwardly into the upper space 58¹ surrounding sleeve 24 whence it flows over the upper edge of sleeve 24, when open, into the cylinder above the piston. Oil is also sucked down from recess 66 into the crank case, where it is splashed by the crank disc 35 so as to reach every moving part in the crank case.

The receptacle 19 into which the lower cylinder 15 discharges serves as an oil reservoir and also as a separator to recover the surplus oil from the discharge of the pump. The condensed water vapor from the crank case, when water is the refrigerating fluid used, settles to the bottom of vessel 19, as is indicated at 66, the oil rising above the water, as is indicated at 67. The oil is drawn upwardly from this space by pipe 65, previously referred to, and is used over again. The water is forced upwardly in a trap 68, by the weight of the oil 67 above the same in vessel 19, the water flowing out through a pipe 69 in trap 68.

The refrigerating apparatus described is inherently self regulating, because as the temperature of the water chamber 1 is lowered, the water vapor withdrawn therefrom through pipe 9 becomes less dense and as the amount of cooling produced in chamber 1 at a given pumping speed is directly proportional to the amount of vapor removed it is directly proportional to the density of the vapor. For example at 40 degrees F temperature one pound of steam occupies 2438 cubic feet, and at 32 degrees F. it occupies 3294 cubic feet. The removal of one pound of steam will produce practically the same amount of cooling at either temperature.

When a greater cooling effect is required in the refrigerator, that is for example when food products are placed in the refrigerator which require cooling, the temperature of water chamber 1 will rise, and the vapor removed will have a greater density. The suction pump runs at constant speed and in removing the vapor of greater density it removes more heat, which is the condition desired. In a like manner when the temperature of the chamber 1 falls less heat will be removed therefrom because of the vapor removed being of lesser density. As stated, the refrigerant will not drop below

the freezing point because the capacity of the constant speed pump is such that at the lower room temperatures which the refrigerant will encounter, there will not be sufficient evacuation to freeze the refrigerant, and at the higher temperatures the inherent property of the saturated vapor as above pointed out, will operate as stated in maintaining the refrigerant temperature within the desired range. The temperature of the refrigerator will accordingly be maintained within a narrow range, this range being not sufficiently great to interfere with the satisfactory operation of the apparatus. As the pump runs continuously no automatic devices for starting and stopping the driving motor are necessary. Those features of my invention which are herein described and not claimed, such as the pump per se and the refrigerating system or apparatus as a whole, are claimed respectively in my co-pending applications Serial No. 582,128, filed August 16, 1922, and Serial No. 581,304, filed August 12, 1922.

It is believed that the method of practicing the process, and also the operation of the apparatus described, will be apparent from the above description. While I have described the preferred manner of practicing the process in connection with the preferred form of apparatus for carrying out the same, it will be understood by those skilled in the art, after understanding the

invention, that various changes and modifications may be made therein without departing from the spirit or scope of the invention, and I do not wish to be understood as limiting myself other than as indicated in the appended claim.

What I claim is:—

Process of refrigerating under regulation by an inherent property of the saturated vapor of the refrigerant to automatically maintain a suitable refrigerating temperature, which comprises, maintaining a body of water at a constant level in a closed space which is to be maintained at a refrigerating temperature above 32° Fah., evaporating the water in said space and removing the vapor by suction, the suction means operating continuously and at a constant speed to remove water vapor at a constant rate volumetrically, the suction means operating at such rate and being so proportioned that it will not freeze the refrigerant under ordinary low temperatures to which household refrigerators are subjected, and will maintain, with the varying density of the vapor, the temperature of said body of water, at approximately the desired point above 32° Fah.

Signed at New York city, in the county of New York and State of New York this 21st day of February A. D. 1922.

KENNETH L. CURTIS.
